UNITED STATES PATENT OFFICE.

BERTHA J. GRANCELL, OF PHILADELPHIA, PENNSYLVANIA.

FOLDING UMBRELLA.

Application filed December 24, 1921. Serial No. 524,719.

To all whom it may concern:

Be it known that I, BERTHA J. GRANCELL, a citizen of the United States, residing at Philadelphia, in the county of Philadelphia and State of Pennsylvania, have invented 5 certain new and useful Improvements in Folding Umbrellas, of which the following is a specification, reference being had to the accompanying drawings.

10 This invention relates to umbrellas and has for its object the provision of an umbrella which is capable of being folded whereby it may be carried conveniently within a suitcase, satchel or the like, the 15 construction being such that the device may be easily extended into operative position and collapsed when desired with very little effort.

An important and more specific object is 20 the provision of a folding umbrella in which the ribs are formed of hinged sections and in which the stick is foldable and ordinarily held in extended position by a telescopic handle, the entire arrangement 25 of all the parts being such that there will be ample strength and rigidity when the device is in extended position.

An additional object is the provision of 30 a folding umbrella which will be simple and inexpensive in manufacture, efficient in use, durable in service and a general improvement in the art.

With the above and other objects and advantages in view, the invention consists in 35 the details of construction to be hereinafter more fully described and claimed, and illustrated in the accompanying drawings, in which:

Figure 1 is a longitudinal sectional view 40 showing the device in extended position;

Figure 2 is a similar view showing the umbrella in closed position before folding;

Figure 3 is a similar view showing it in 45 closed and folded position;

Figure 4 is a side elevation showing the entire device closed and folded;

Figure 5 is a section on the line 5—5 of 50 Figure 2;

Figure 6 is a detail sectional view showing the manner of folding the handle sections and the locking member therefor;

Figure 7 is a detail view partially in section showing the manner of locking the ribs of the umbrella in extended position; and

55 Figure 8 is a detail perspective view showing the joint employed in the ribs and

the manner of rigidly connecting the same in open position.

Referring now more particularly to the drawings, I have shown my umbrella as 60 comprising a central supporting stick which includes a pair of hollow sections 10 and 11 hingedly connected, as at 12, at their adjacent ends. The free end of the section 10 carries a ring 13 and the free end of the section 11 is formed with an inturned flange 14.

The numeral 15 designates a handle member which is telescopically engaged within the section 11 and which is provided with a head 15^a which engages against the inturned flange 14 of the section 11 to limit the outward movement thereof. To this handle member 15 or the head 15^a thereof is secured an extension 16 which is pivotally connected by a link 17 to a bracing member 18.

The combined lengths of the extension 16, link 17 and bracing member 18 are such that when the head 15^a is engaged with the flange 14 of the section 11 the bracing member 18 extends across the hinged connection of the sections 10 and 11 to rigidify the same. When the handle member 15 is pushed into or telescoped in the section 11, the link connection 17 of the extension 16 and bracing member 18 is so aligned with the hinged connection as to permit of the folding together 75 of the two sections. It will be noted that when the sections are folded together the handle member 15 is automatically locked 80 to prevent its sliding out of the section 11.

To prevent accidental telescoping of the handle member 15 into the section 11 when the umbrella is in raised position, any suitable catch, such as a spring latch 19, may be employed. The section 10 is provided adjacent the hinged end thereof with a shoulder ring 20 for a purpose presently to appear.

The numeral 21 designates a plurality of ribs which are formed in sections 22 and 23, 100 hingedly connected at their meeting ends, as indicated at 24. The free ends of the sections 22 are pivotally connected with the ring 13 in such a manner as to be capable of a limited circumferentially shifting movement thereon and the fabric covering 25 is secured to the ribs in the customary manner.

Slidable upon the section 10 of the stick is a runner 26 with which are pivotally connected stay rods 27 having their free ends 110 pivotally connected with the locking members 27^a as shown. These locking members

are in the form of sleeves of sufficient length to cover and rigidify the joint of the rib sections 22 and 23 and operate between pins 27^b and 27^c secured to the rib sections 22 and 23 respectively. The runner member 26 is provided with spring catches 26^a which engage with the shoulder ring 20 when the ribs 21 are fully extended and the locking members 27^a bridging the hinged connections 10 of the sections 22 and 23 thereof.

When it is desired to fold the ribs the runner member 26 is forced upwardly past the center point after which it will move easily toward the head or upper end of the 15 of the stick. As the runner member 26 approaches the upper end of the stick, the locking members 27^a are withdrawn sufficiently to uncover the hinged connection of the sections of the ribs 21 permitting closing 20 of the ribs and the folding of the outer sections 23 thereof back upon the sections 22 in the manner illustrated in Figures 3 and 4.

In folding the handle the spring 19 is released and the handle member 15 forced inwardly to its limit, aligning the link 17 with the hinged connection. At this time, as hereinbefore stated, the handle may be folded, lying exteriorly of the ribs and alongside thereof, forming a very compact 30 bundle. If desired, the stick section 11 may have secured thereto an elastic band 28 which may be snapped about the ribs and handle section to prevent movement of the free ends, as illustrated in Figure 4.

From the foregoing it is believed to be obvious that I have devised an umbrella of the folding type which is extremely simple in construction and operation and which may be cheaply manufactured. It will likewise be obvious that many changes are possible in the shape, size and arrangement of the various parts herein shown without in any manner departing from the spirit of my invention or the scope of the subjoined 45 claims.

I claim:

1. In a folding umbrella, a stick comprising a pair of hingedly connected sections and a handle telescoping within one of the 50 sections, and means connected with said han-

dle preventing withdrawal of said handle when the stick is in folded position and preventing folding of the stick when the handle is in withdrawn position.

2. In a folding umbrella, a stick comprising a pair of hingedly connected sections and a handle telescoping within one of the sections, and means connected with said handle and operative when the handle is extended rigidifying the hinged connection of said sections. 55

3. In a folding umbrella, a stick comprising a pair of hingedly connected sections and a handle telescoping within one of the sections, and means connected with said handle and operative when the handle is extended rigidifying the hinged connection of said sections, said means likewise preventing extending of the handle when the stick sections are in folded position. 60

4. In a folding umbrella, a stick comprising a pair of hingedly connected tubular sections, a handle telescoping within one of the sections, a rigid member slidable within the stick, a link connecting the rigid member and handle, said rigid member aligning with the hinged connection of the sections to rigidify the same when the stick is in the open position, said link aligning with the hinged connection when the handle is in the closed position and permitting folding of the stick. 70

5. In a folding umbrella, a stick comprising a pair of hingedly connected tubular sections, a handle telescoping within one of the sections, a rigid member slidable within the stick, a link connecting the rigid member and handle, said rigid member aligning with the hinged connection of the sections to rigidify the same when the stick is in the open position, said link aligning with the hinged connection when the handle is in the closed position and permitting folding of the stick, and means on the handle and cooperating with the stick for limiting the movement of the handle with said link aligned with said hinged connection. 85

In testimony whereof I hereunto affix my signature.

BERTHA J. GRANCELL.
